UNITED STATES PATENT OFFICE

2,034,225

ORE CONCENTRATOR

Charles E. Bye, Kansas City, Kans.

Application August 9, 1934, Serial No. 739,148

5 Claims. (Cl. 209—439)

My invention relates to a machine for recovering the smallest particles of gold or other precious metals which usually accompanying gravel, auriferous sands, dust, etc., and one object is to provide an efficient machine of this character which is simple in construction and economical to operate.

A further object is to provide a dry process gold machine which may be operated successfully in localities remote from a water supply.

Another object is to provide a machine of this character which may be operated continuously over long periods of time as the construction is such that stoppage of the machine is unnecessary when taking on materials for separation, or for removal of the separated materials.

In carrying out the invention I employ the forces of gravity, agitation and air blasts in effecting the separation of precious metals from the waste products; and in order that the invention may be fully understood reference will now be had to the accompanying drawings, in which:

Fig. 1 is a side elevation of the machine.

Fig. 2 is a plan view of the machine with the hopper removed.

Fig. 3 is a detail plan view of an inverted conical plate employed in carrying out the invention.

Fig. 4 is a broken vertical cross section on line 4—4 of Fig. 2 with the frame removed and some of the parts in elevation.

Fig. 5 is an enlarged fragmentary cross section on line 5—5 of Fig. 2.

In carrying out the invention I employ a suitable frame comprising in the present instance standards 2, 4 and 6, and a longitudinal member 8 fixed upon the standards 2 and 4. If the machine is to be made portable as shown the foregoing frame is mounted upon a sled comprising a pair of runners 10 and a platform 12 uniting said runners.

Referring now more particularly to the mechanism for handling and separating the materials, 14 designates a horizontally-disposed conical plate provided with a depending hub 16 operably mounted upon a stationary shaft 18 supported in any suitable manner as in the socket 20 of a base plate having a flange 22 firmly secured upon the platform 12 of the sled.

The upper, or concentrating surface of the conical plate 14 is equipped with a fixedly-mounted, centrally located tubular feeder 24 provided at its lower portion with outlets 26. The tubular feeder 24 is supplied from a hopper 27 with the materials to be separated.

The upper surface of the conical plate 14 is provided with a suitable number of fixedly mounted spiral riffles 30 spaced equally apart and extending from the base of the feeder 24 to the circumference of the conical plate 14. The spiral riffles 30 consist preferably of heavy strands of wire which cooperate with the inclined surface of the conical plate 14 in providing approximately V-shaped grooves 32, Fig. 5, wherein the fine gold is collected as the coarser and baser materials roll downwardly by the force of gravity over the conical plate 14 and descend upon an inverted horizontally-disposed conical plate 34 fixed to said conical plate 14 by a plurality of tubular fastening means 36.

In order to facilitate the separation of the materials agitation of the conical plates 14 and 34 is resorted to to aid the force of gravity and the spiral riffles 30. Agitation of said conical plates may be effected in any suitable manner. In the present instance I have shown mechanism for that purpose comprising an arm 38 projecting laterally from the lower margin of said conical plate 14, a pitman 40 connected at one end to said arm 38 and projecting at its opposite end into the path of a rotary cam 42 fixedly mounted upon a rotary shaft 44 driven by a pulley 46 and journaled in bearings 48 secured to the standards 4 and 6.

The pitman 40 is held in a horizontal position by means of the arm 38 and upper and lower guide rollers 49, which latter are mounted upon shafts 51 projecting from bearings 53 mounted upon the member 8. The conical plate 14 is partially rotated in one direction by the pitman 40 and partially rotated in a reverse direction by a coil spring 50 mounted in a slot 52, in the frame member 8, and bearing at one end against a box 54 reciprocably mounted in the slot 52 and connected to the arm 38. A short coil spring 56, located in the slot 52, is provided to cushion the end of the reverse stroke to avoid the undue shock which otherwise would be imparted to the machine if the box 54 were permitted to impinge directly against the adjacent end of the slot 52.

The pitman 40 and the box 54 are loosely connected to the arm 38 to permit the latter, when in motion, to describe an arc with the conical plate 14, while the pitman and the box move back and forth in a straight line.

Compressed air is provided to cooperate with the spiral riffles 30 and the respective forces of gravity and agitation in separating the materials. The compressed air may be obtained from any suitable source. In the present instance I have

shown such source in the form of a suitably driven blower 58 from which air under pressure is conducted upwardly through a suitable number of flexible tubes 60 secured at their upper ends by 5 clamps 62 to an equal number of air spreaders 64 fixed at their lower ends to the conical plate 14 near the outer margin thereof.

Preferably, the air spreaders 64 are equal in number to the spiral riffles 30 and located near 10 the respective ends of narrow passageways 66 formed by the lower portions of said spiral riffles 30, the lower portions of the air spreaders 64 and a number of elements 68 fixed to the upper surface of the conical plate 14. The elements 15 68 consist preferably of short lengths of wire of the same gage as those comprising the spiral riffles 30. The air spreaders 64 are curved, as shown, to direct the air blasts across the passageways 66 which lead to respective outlets 70 formed 20 by registering openings in the conical plate 14 and the tubular fastening means 36, which latter are provided with depending nipples 72 extending through the inverted conical plate 34 and equipped with tubes 74 leading to containers 76 25 resting upon the platform 12 of the sled.

Reverting to the inverted conical plate 34 it will be seen (Figs. 3 and 4) that it is provided on its concentrating surface with a suitable number of spiral riffles 77 which extend around in a reverse 30 direction to the spiral riffles 30 to cooperate with the forces of gravity and agitation in conducting the material to an opening 78 formed in the lower central portion of said inverted conical plate 34. A spout 80 is fixed to the under side of the conical 35 plate 34 to carry off the waste material falling through the opening 78.

The inverted conical plate 34 is provided with outlets 79 communicating with flexible tubes 80 leading to containers 82. The outlets 79, like 40 the outlets 70, are too small to admit large particles of waste material but allow any fine gold which may be present to descend into the containers 82 through the tubes 80a.

Briefly stated the operation is as follows: When 45 the machine is in operation the materials are uniformly distributed over the upper portion of the conical plate 14 as they pass from the outlets 26 of the feeder 24. The gravel and coarser pieces of waste material roll downwardly over the conical plate 14 and the spiral riffles 30 and fall into the inverted conical plate 34, from which they 50 pass through the outlet 78 into the spout 80 which discharges them to one side of the machine. The fine gold, however, is caught in the V-shaped 55 grooves 32 formed by the upper surface of the conical plate 14 and the spiral riffles 30 and traverses a spiral course in the direction of the arrows *a*, Fig. 1, from the feeder 24 to the outlets 70. As the reverse movement imparted to the 60 conical plates 14 and 34 by the spring 50 is checked by the spring 56 more suddenly than the forward movement imparted by the pitman 40, it is apparent that the momentum thus acquired 65 by the fine gold will cause it to travel downwardly in the spiral V-shaped grooves 32 to the respective outlets 70. As the fine gold passes through the passageways 66 on its way to the outlets 70 any sand or dust mixed with the gold is blown away by the air blasts discharged from 70 the respective flexible tubes 60.

From the foregoing it is apparent that I have provided a machine which is well adapted for the purpose intended, and while I have shown one embodiment of the invention I reserve all rights 75 to such changes and modifications thereof as

properly fall within the spirit and scope of the invention as claimed.

Having thus described my invention, what I claim and desire to secure by Letters Patent, is:

1. A machine of the character described comprising a horizontally-disposed conical concentrating plate operably mounted and provided near its lower margin with outlets, means for actuating said conical plate, spiral riffles fixed upon the concentrating surface of said conical plate and extending from a point near the apex thereof to a point near the respective outlets, means fixed upon the conical plate and cooperating with the lower portion of the spiral element in forming narrow passageways leading to the respective outlets, a blower tube leading from said blower to point adjacent the respective passageways, and air spreaders secured to the conical plate and connected to the discharge ends of the respective tubes for directing air from the blower across the passageways.

2. A concentrator of the class described comprising a horizontally-disposed conical plate operably mounted and provided with spaced outlets near its lower margin, a feeder adapted to discharge materials upon the upper portion of said conical plate, spiral riffles secured upon the concentrating surface of said plate and extending from the upper portion to the lower portion of the latter and adapted to direct concentrates to the respective outlets, means for discharging air blasts, air spreaders spaced from the lower portions of said spiral riffles to cooperate therewith in directing the concentrates to the respective outlets, the air spreaders being adapted to direct the respective air blasts across the spaces between the spiral riffles and said air spreaders, and means for agitating the conical plate.

3. A concentrator of the character described comprising a horizontally-disposed conical plate operably mounted and provided with spaced outlets near its lower margin, a feeder adapted to discharge materials upon the upper portion of said conical plate, spiral riffles secured upon said plate and extending from the upper to the lower portion thereof and adapted to direct concentrates to the respective outlets, means for discharging air blasts, air spreaders spaced from the lower portions of said spiral riffles to form narrow passageways leading to the outlets, said air spreaders being curved for directing the respective air blasts across said narrow passageways, an inverted horizontally-disposed conical plate of greater diameter than the first-mentioned conical plate and arranged directly beneath the latter, said inverted conical plate having a centrally-disposed discharge opening, conical riffle means fixed upon said inverted spiral plate and extending from the upper to the lower portion of the latter, a shaft upon which the conical plates are mounted, and means for agitating said conical plates.

4. A concentrator of the character described comprising a horizontally-disposed conical concentrating plate operably mounted, means for differentially actuating said plate, outlets leading downwardly from said conical plate near the outer margin of the latter, narrow passageways on the concentrating surface of said conical plate leading to said outlets, means for discharging air blasts, and air spreaders adjacent the respective outlets and adapted to direct the air blasts across the respective passageways.

5. A concentrator of the character described

comprising a horizontally-disposed conical concentrating plate operably mounted, means for differentially actuating said plate, outlets leading downwardly from said conical plate near the outer margin of the latter, narrow passageways on the concentrating surface of said conical plate leading to said outlets, means for discharging

air blasts, flexible tubes connected to said air blast discharging means, and air spreaders fixed upon the conical plate and to which the discharge ends of said flexible tubes are connected, said air spreaders being curved to direct the air blasts 5 across the respective passageways.

CHARLES E. BYE.
